PERMANENT WAVE WINDER

Filed July 1, 1929

Fig. 1.

UNITED STATES PATENT OFFICE

STEPHEN JOHN DURANEY, OF JOHNSTOWN, PENNSYLVANIA, ASSIGNOR OF ONE-HALF
TO SAMUEL RICHARD BLOCK, OF JOHNSTOWN, PENNSYLVANIA

PERMANENT WAVE WINDER

Application filed July 1, 1929. Serial No. 375,068.

My invention relates to improvements in permanent wave winders for applying or winding hair on permanent wave rods and the objects of my invention are:

5 *First.*—To permit one to wind or wrap strands of hair upon plain round rods which are mostly used in permanent waving.

10 *Second.*—To wind the hair to the said rods mechanically without adding any more weight to the rod or head than is required with hand winding.

I attain these objects by the means illustrated in the accompanying drawings in which:

15 Figure 1 is a side view of the permanent wave winder.

Figure 2 is a sectional view on line 2—2 of Figure 1.

Figure 3 is a view of the opposite side.

20 Figure 4 is a view of the winder and its application.

Figure 5 is a sectional view showing the inside of the knob.

25 In the embodiment of my invention illustrated I have shown the same adapted to cooperate with a permanent wave rod of cylindrical formation, such as is in use in the greater number of permanent wave machines today. It is understood, however, that my

30 device may be utilized with machines using rods having planar surfaces or of otherwise suitably formed construction without departing from the spirit of my invention.

35 In this form of the invention then the handle portion 1 having the cylindrical, chamfered part for acting as a finger hold during the operation and the body part 2 is axially bored as shown at 3 for close sliding relationship with the rod. It will be easily un-

40 derstood that this bore will guide the device along the rod during the operation. The bore is flared at its inner extremity as shown at 4 in Figure 5 to facilitate passage of the rod from the bore to the winding chamber soon to be described, during the positioning 45 of the winder on the rod.

The winding chamber 5 is of cylindrical formation and of greater internal diameter than bore 3, thus providing an annular space 50 between the inner walls thereof and the rod.

It has an opening 6 therein of rectangular formation with the exception of one side which is tapered. The walls of the chamber are so formed on this fourth side that a slot communicating with the opening is provided, 55 running to the extremity of the chamber. This slot appears most clearly in Figure 2. The chamber is connected to the handle portion 1 by means of the tapered wall 7.

The portion of the chamber 5 adjacent the 60 slot is extended outwardly as shown at 8 to form a lip, which cooperates with the part of the wall indicated at 9 to guide the hair through the slot and into the opening 6 as will be described later in the specification. 65 The upturned part 10 of the lip 8 and the cutaway part of the wall 9 also serve to facilitate this passage of the hair.

From the foregoing description the use and operation of my device is easily understood. 70 The operator places the winder on the rod in the manner shown in Figures 2 and 4. He then ties the lock of hair to the rod, which is usually bifurcated for this purpose as shown at 12, the tie being made about an 75 inch from the scalp 13 of the head being worked upon, as is well known to those skilled in the art.

The hair is then placed between the lip 8 and the wall 9 and drawn into the opening 80 6 as shown in Figure 4. The operator then turns the winder until the axially extending rectilinear edge of opening 6 is brought into close engagement with the hair and continues such turning motion, while at the same time 85 slowly advancing the winder along the rod. This motion will cause the hair to be wound upon the rod in the manner shown at 14. The unwound hair will be held in proper position by the lip 8 as shown at 15 during 90 this operation.

When the hair is nearly wound upon the rod, the operator places a strip of gauze or crepe wool under the lip 8, which is tied onto the rod with a strand of twine after the winding operation leaving the hair securely wound and fastened upon the rod. 95

It is thus seen that I have provided a winder for use in combination with permanent wave machines that easily and efficient- 100

ly accomplishes the hair-winding operation without the necessity of extensive and skillful manual operations.

It will further be noted that because of the rectangular construction of the hair-engaging walls of the opening in the winding chamber, and the tapered formation of the remaining wall, the hair will be wound upon the rod with an evenness and uniformity not easily attained by manual means.

I claim:

1. A device for winding hair or the like on a rod, comprising a chamber having an opening therein and a slot communicating with said opening for admitting the hair thereinto, the walls of the chamber forming said slot being in overlapping relationship, whereby to facilitate entry of hair thereinto.
2. A device for winding hair or the like on a rod, comprising a chamber having an opening therein, and a slot communicating with said opening for admitting the hair thereinto, and a lip extending in overlapping relationship to the wall of said chamber and above said slot to retain the hair in said opening.
3. A device for winding hair or the like on a rod, comprising a chamber having an opening therein and a slot communicating with said opening for admitting the hair thereinto, and a lip extending in overlapping relationship with the wall of said chamber adjacent the slot, said lip being bent outwardly adjacent the mouth of said slot for facilitating entry of the hair into said slot.
4. A device for winding hair or the like on a rod, comprising a chamber having an opening therein and a slot communicating with said opening for admitting the hair thereinto, and a lip extending over said slot, said lip being curled outwardly to retain the hair thereabove during the winding operation.

STEPHEN JOHN DURANEY.
